UNITED STATES PATENT OFFICE.

NELSON L. TUCK, OF PHILADELPHIA, PENNSYLVANIA.

AUTOMATIC FILLING AND WEIGHING MACHINE.

SPECIFICATION forming part of Letters Patent No. 417,609, dated December 17, 1889.

Application filed January 29, 1889. Serial No. 297,997. (No model.)

To all whom it may concern:

Be it known that I, NELSON L. TUCK, a citizen of the United States, residing in Philadelphia, Pennsylvania, have invented certain 5 Improvements in Filling and Weighing Machines, of which the following is a specification.

The object of my invention is to automatically fill and weigh boxes or other receptacles, as fully described hereinafter.

In the accompanying drawings, Figure 1 is a side view of my improved automatic filling and weighing machine. Fig. 2 is an end view looking in the direction of the arrow, Fig. 1, 15 with the hopper in section. Fig. 3 is a sectional plan on the line 1 2, Fig. 1. Fig. 4 is a sectional plan on the line 3 4, Fig. 1. Fig. 5 is a sectional plan on the line 5 6, Fig. 1. Fig. 6 is a detached perspective view of the 20 hoppers or funnels. Fig. 7 is a detached perspective view of the platform carrying the boxes to be filled. Fig. 8 is a detached perspective view of a portion of the machine, illustrating one of the features of my invention; and Figs. 9 and 10 are detached views 25 of details of my invention.

A is the frame of the machine, mounted on a suitable base A', the frame A carrying a hopper B, having an outlet-spout b. Projecting from the base A' is a boss or step a, 30 in which a vertical shaft C finds its bearing. On this vertical shaft C is a disk D, as shown more clearly in Fig. 7, said disk carrying a series of cups d, having flanges d'. These 35 cups are suspended by their flanges in orifices in the disk D. In each cup is a spring e', carrying a platform e, although in some instances the spring may be dispensed with and the platform carried directly by or forming part of the cup d. On the upper portion 40 of the shaft is a funnel-frame F, having a series of tubular projections, more clearly shown in Fig. 6, these tubular projections fitting into the boxes to be filled, which are 45 mounted on the platforms e. In the drawings I have shown cylindrical boxes x, but it will be understood that boxes of any shape can be filled on the machine, and I preferably make the projections f of a shape to correspond with the shape of the opening in the box. The funnel-frame F has a series of partitions g, which come up to a comparatively

sharp edge g' and taper to the openings f' in the projections f, dividing the frame into a series of compartments which act as funnels 55 for the series of boxes to be filled.

The disk D and frame F, with the boxes to be filled, are intermittently rotated by mechanism described hereinafter, and the object of making the comparatively sharp edges 60 g' on the partitions is that the flow of the material into the box will be cut off immediately and caused to enter the adjoining funnel, as it will be understood that the feeding of the material is continuous as long as 65 there is material in the hopper. Directly under the disk D is the weighing mechanism, which I will now proceed to describe.

The balance-beam H is pivoted in standards h h, projecting from the base A'. The 70 beam is irregular in form to adapt it to the irregularities of the machine, and composed of two longitudinal bars h', connected together at intervals by cross-bars h''. On the rear cross-bar h'' is suspended a balance-weight i, to which can be added the weight 75 of the required denomination.

In line with hopper B, at the front of the machine, is a vertical supporting-rod I, having a cross-head I', with openings in which 80 are pivoted the knife-edges j j of the bar h³ of the scale-beam H. This rod I is continued through the base of the machine, and is connected to a depending lug a' by a rod j', so that the rod is kept at all times in a vertical 85 position. On the upper portion of the rod I is a head k, having a platform k', as shown more fully in Fig. 9. The outer end of this platform k' is bent, as shown, so that when it is depressed, as described hereinafter, and 90 the disk D is turned, the cup adjoining that being filled will readily ride over the inclined portion into position directly under the spout b of the hopper.

On one side of the beam H is secured a 95 screw-rod l, having a weight l', which is a regulating-weight used on scale-beams of this class.

I will now describe the mechanism for turning the platform carrying the boxes, and also 100 the mechanism for stirring the material in the hopper, and the device for packing the same in the boxes.

J is a vertical shaft stepped in a bearing m

in the base of the machine and journaled at its upper end in a bearing m' in the frame A. This shaft J is driven in the present instance through the medium of a belt-wheel J', which is mounted on the shaft, or said shaft can be driven by other means than that shown without departing from my invention.

Secured to or forming part of the shaft J is a friction-disk K, and above this friction-disk and adapted to slide upon the shaft is a friction-disk L, having a sleeve L', and between this sleeve and a collar m^2 on the shaft is a spring n , which tends to force the friction-disk L against the friction-disk K. On the friction-disk L are a series of pins or projections p , which project on both sides of the disk L, as shown in Fig. 1. The projections on the upper side fit into radial slots q in the disk D, and through the medium of these pins the disk is turned in the present instance one-sixth of a revolution as each pin comes around. This is what is commonly called the "star-wheel movement."

The movement of the friction-disk L, and consequently of the disk D, is governed by the scale-beam H. On the beam H is a lug r , which when the beam tilts strikes a trigger s. This trigger is pivoted to a spring-plate S, secured to the frame of the machine. The trigger s has a lip s' at its inner end, so that when the beam H is moved by the weight of the box being filled the lug rises in the direction of the arrow, Fig. 1, moving the trigger on its pivot and throwing down the lip s' , so as to bring it in line with a pin t on the shaft J, or, as is the case in this machine, on the hub of the disk K, which is secured to the shaft. The pin t rides upon the lip s' and presses upon the trigger s and forces the spring-plate S down in the direction of the arrow, Fig. 8. The plate S has a lip u at its outer end, which engages with the projection p on the under side of the disk L, so that as said plate S is depressed it moves the lip u away from the pin p and allows the disk L to turn, and consequently turn the disk D, the spring n creating enough friction for the purpose. As the disk turns the cup carrying the filled box is moved off of the platform k' of the weighing mechanism and an empty box is moved into position thereon, the scales assuming their normal position, and the lug r , being free from the trigger s, allows it to fall to its normal position, so that the lip s' of the trigger will be out of the line of the pins t on the shaft.

On the upper portion of the shaft J is a gear-wheel v , which meshes with an intermediate wheel v' on a stud v^2 . This intermediate wheel meshes with a gear-wheel v^3 on the shaft V, which carries the pronged stirrer V', as fully shown in Fig. 2. This stirrer can be of any of the forms used in connection with hoppers for keeping the material in the hopper agitated.

I will now describe the mechanism for pack-

ing the material in the boxes after being weighed.

Secured to the shaft J is a cam U, of the form shown in Fig. 10, and situated directly above this cam is a pivoted block U', pointed at one or both ends and adapted to the groove in the cam. This block U' is pivoted to a lever W, pivoted at w to the frame of the machine and having a short arm w' , which is secured to one end of a spring y, the opposite end being secured to the base of the machine. This spring tends to keep the lever W in the position shown in Fig. 1. A weight may be substituted for this spring without departing from my invention. A rod W' forms a continuation of the long arm of the lever, and is detachably secured thereto, and is bent at the outer end and provided with a thread w^3 , to which is adapted a nut w^2 and a plunger W² of a shape to fit the orifice in the frame F. The lever W and its plunger are only moved when a trigger Y, pivoted at y' to the frame of the machine, guides the block U' in the slot in the cam U. One arm 90 of this trigger rests directly above one end of the block U', and the opposite arm of the trigger has a bearing-surface z' , against which the pins on the upper side of the plate L bear, a spring z^2 tending to force the trigger in the direction of its arrow, Fig. 1, and the pin z^3 acting as a stop to limit its forward movement. The projections as they strike the bearing-surface z' of the trigger force the same in a direction opposite that indicated by the arrow, causing the finger z to push the end of the block U' into the cam-slot in the cam, so that as the cam revolves the block will follow the cam-slot and cause the lever W, carrying the plunger, to move in the direction of its arrow, thus compressing the material in the box previously filled. As the pin p reaches the point z^4 on the bearing-surface z' of the trigger Y the trigger is released and assumes its normal position—that is, the position shown in Fig. 1—and is not moved again until a second pin strikes the cam or bearing-surface and moves the trigger, forcing the cam-block in the slot of the cam, as previously described.

The upward movement of the lever W is limited by an adjustable bar X, secured to the frame A of the machine by a nut b' , the lower portion of the rod striking the cam-block and tending to keep said block in proper position, so as not to engage accidentally with the cam-slot. Thus the different parts of the machine are perfectly rigid and only act as dictated by the weighing mechanism.

In the operation of filling the boxes or packages the material is placed in the hopper and the boxes are placed by the attendant one after the other on the platforms e, carried by the disk D, and under the frame F. The box is thus carried with the two frames, but can be readily removed therefrom by merely

compressing the spring, allowing the top of the box to clear the projections *f* of the frame *F*. As the frame and disk revolve, the material, which flows continuously from the spout, is cut off from one compartment by means of the partition *g* and commences at once to flow into the next succeeding box. It should be understood that the weights used in connection with this machine must be graduated according to the speed at which one box takes the place of the other, as the material from the hopper is flowing into the boxes during the transfer of a filled box away from the line of flow and the movement of an empty box into position to be filled. After a box has been filled and moved from off the scale-platform it is packed by the plunger *W*², after which the filled box can be removed by the attendant and an empty box inserted in its stead.

It will be understood that the machine shown in the drawings is constructed for use in filling small boxes or cans, and that a machine constructed to fill larger boxes will necessarily be altered in detail without departing from my invention.

I claim as my invention—

1. The combination, in a machine for automatically filling, weighing, and packing boxes, of the hopper, and a spout through which the material continuously flows, with weighing mechanism and a box-carrier, and a funnel-frame for the boxes, mechanism for moving the boxes and funnel-frame into and out of line with the spout of the hopper, as the weighing mechanism dictates, without waste of the material being packed, substantially as specified.

2. The combination of the hopper, the spout through which the material has a continuous flow, the disk carrying the boxes to be filled, a frame *F*, by which the material is guided into said boxes, said frame having a series of partitions, so that on the movement of one box out of line with the spout and the movement of another box into line with the same the partition will cut off the flow of material into one box and allow it to flow into the other box, substantially as described.

3. The combination of the hopper, the intermittently-moved box-carrier having cups on which are supported the boxes to be filled, with weighing mechanism and a platform adapted to support the cup and box being filled, substantially as specified.

4. The combination of the hopper, the intermittently-rotated shaft *C*, disk *D*, carrying platform *e*, springs *e'*, with a funnel-frame *F*, having projections *f* for holding the boxes to be filled in place on the platform *e*, substantially as specified.

5. The combination of the hopper, box-carrying disk *D*, having radiating slots *g*, an intermittently-rotated disk *L*, having pins *p*,

adapted to engage with the slots in said disk, 65 substantially as described.

6. The combination of the hopper, the box-carrying disk *D*, driving-shaft *J*, a friction-disk *K*, secured thereto, a friction-disk *L*, adapted to drive said disk *D*, with a stop-plate *S* for said disk *L*, with a scale-beam adapted to trip said plate and release the disk *L*, substantially as set forth.

7. The combination of the hopper, the rotated box-carrying disk, and the scale-beam, 75 with the shaft *J*, having a friction-disk, a friction-disk *L*, adapted to drive the box-carrying disk and having pins *p*, a spring-plate engaging one of said pins, a trigger *s*, and pins *t* on the shaft, adapted to engage with 80 the trigger and depress the plate *S* when the weight of the box overbalances the scale-weight, substantially as specified.

8. The combination of the scale-beam, the projection *r* thereon, a friction-disk *L*, having 85 a pin *p*, a spring-plate *S*, engaging said pin, with a trigger *s*, pivoted to said plate, and having a lip *s'*, and pins *t* on the shaft, the whole combined and acting substantially as described.

9. The combination of the intermittently-rotated box-carrier *D*, a driver-cam *U*, with a packing-plunger *W*², pivoted to a lever *W*, said lever having a pivoted cam-block adapted to the slot of the cam *U*, and a trigger *Y*, adapted to press on the pivoted cam-block and direct it into the slot of the cam, 95 substantially as described.

10. The combination of the box-carrying disk *D*, the shaft *J*, the disk *L*, having pins 100 *p*, and a cam *U*, a lever *W*, having a packing-plunger *W*², and a cam-block, with a trigger *Y*, one arm of which is adapted to be acted upon by a pin *p* on the disk *L*, and the other arm adapted to act upon the cam-block and 105 to throw it into the groove in the cam *U*, substantially as and for the purpose described.

11. The combination, in a box-filling machine, of the rotated carrying-disk *D*, supporting the box to be filled, with a funnel-frame having partitions *g*, which form the funnels for the different boxes, said partitions terminating in a knife-edge *g'*, substantially as shown and described.

12. The combination of the shaft *J*, the cam 115 *U* thereon, and a lever *W*, carrying a packing-plunger, with a pivoted cam-block carried by said lever, and a stop-bar *X*, acting to limit the upward movement of said lever *W* and at the same time steady the cam-block, 120 substantially as shown and described.

In testimony whereof I have signed my name to this specification in the presence of two subscribing witnesses.

NEILSON L. TUCK.
